UNITED STATES PATENT OFFICE.

JEDDY D. NIXON, OF HOUSTON, TEXAS, ASSIGNOR TO HOWARD F. SMITH, OF HARRIS COUNTY, TEXAS.

TONG.

Application filed March 6, 1922. Serial No. 541,609.

To all whom it may concern:

Be it known that I, JEDDY D. NIXON, a citizen of the United States, residing at Houston, in the county of Harris and State of Texas, have invented certain new and useful Improvements in a Tong, of which the following is a specification.

This invention relates to new and useful improvements in a tong.

One object of the invention is to provide a tong of the character described which is specially adapted for use in turning pipes and bodies of similar contour, in the process of screwing together and unscrewing the joints thereof.

Another object of the invention is to provide a tong which may be easily applied and released from the pipe and which will securely grip and turn the same.

Another object of the invention is to provide a tong which is of simple construction and may be cheaply and easily manufactured.

With the above and other objects in view the invention has particular relation to certain novel features of construction, operation, and arrangement of parts, an example of which is given in this specification and illustrated in the accompanying drawings, wherein:

Figure 1 is a plan view of the tong, and Fig. 2 is a side view thereof.

In the drawings, the numeral 1 designates the pipe to be turned. The numeral 2 designates the head of the tong, whose side adjacent the pipe is arcuate to conform to the contour of the pipe. The outer end of this head is slotted to receive the inner end of the handle 3 which fits into said slot and which is pivotally secured therein by means of a suitable bolt 4. The inner end of the handle has a lateral projection 5 formed integrally therewith. Pivoted to the head 2 there is a clamp 6 which is arcuate in form and to the free end of this clamp there is pivoted a latch 7 having the slot 8 therethrough.

The clamp 5 has a serrated jaw 9 inserted in a dove-tailed groove in the inner side of the clamp 6, and is arcuate in form 50 to conform to the pipe. This jaw may be removed and replaced with a new one when its teeth become dull.

When the tong is applied to the pipe, the latch is engaged over the projection 5, which fits through the slot 8, and whose outer side is slightly concave to form a seat for the outer end of the latch. The wrench is manipulated in the direction indicated by the arrow in Fig. 1, the handle 60 forming a lever which is fulcrumed on the bolt 4, and the projection 5, acting through the latch 7, operates to clamp the jaw 9 securely against the pipe, the head and jaw thus gripping the pipe and the teeth of said jaw preventing the slippage of the tong on the pipe. The tong may be easily released by pulling the handle 3 reversely and disengaging the latch from the projection 5.

What I claim is:

A pipe tong including a head having a deep slot at one side, an arcuate lateral extension carried by the other side of the head, a single handle one end of which is pivoted in said slot, a lateral projection carried by the pivoted end of the handle and projecting out beyond the slotted end of the head, an arcuate clamp one end of which is pivoted to the free end of said extension, a U-shaped latch pivoted to the other end of said clamp and working substantially parallel with the handle and adapted to engage over said projection, the inner side of said head and extension being arcuate and forming a jaw adapted to conform to the contour of the pipe, and a toothed pipe-engaging grip carried by the inner side of said clamp.

In testimony whereof I have signed my name to this specification.

JEDDY D. NIXON.
